UNITED STATES PATENT OFFICE.

ANDREW L. RIKER, OF BRIDGEPORT, CONNECTICUT, ASSIGNOR TO THE
"LOCOMOBILE" COMPANY OF AMERICA, OF NEW YORK, N. Y., A COR-
PORATION OF WEST VIRGINIA.

AUTOMATIC CIRCUIT MAKING AND BREAKING DEVICE FOR AUTOMOBILES AND THE LIKE.

No. 823,811.

Specification of Letters Patent.

Patented June 19, 1906.

Application filed October 8, 1903. Serial No. 176,223.

To all whom it may concern:

Be it known that I, ANDREW L. RIKER, a citizen of the United States, residing at Bridgeport, in the county of Fairfield and State of Connecticut, have invented an Improvement in Automatic Circuit Making and Breaking Devices for Automobiles and the Like, of which the following description, in connection with the accompanying drawings, is a specification, like characters on the drawings representing like parts.

My invention aims to improve automatic devices for making and breaking electric circuits—such, for instance, as the sparking circuits for internal-combustion engines and the like—such devices being sometimes known as "vibrators" and "tremblers." Automatic devices of this character as heretofore made have usually employed an electromagnet the armature of which has been provided with a resilient or spring-like contact member, which upon attraction of the armature has been moved to interrupt or break the circuit between it and its co-operating fixed contact. An objection to devices of this general character is that they lack a certain positiveness of action which is essential to the production of strong and effective sparking. The resilient nature of the contact arm or member tends to produce imperfect contacts and only partial or imperfect breaks, with the result that the armature and its connected parts partake of a vibrating or buzzing movement without at any time sufficiently making or breaking the circuit to provide a clear and efficient sparking. My invention overcomes this objection and insures always a pronounced making and breaking of the circuit with highly-efficient sparking by means which will best be understood from a description of one form of device illustrating the same and shown in the accompanying drawings.

In the device illustrated the armature always partakes of a definite movement in both directions and brings up against a fixed stop at the end of each of its movements, and the contact member, which is moved or controlled by the armature, likewise has a sharp and positive movement free from the lag or

indefiniteness which characterizes a resilient member.

In the accompanying drawings, Figure 1, in side elevation, illustrates one form of device embodying my invention; Fig. 2, a left-hand end view of Fig. 1; and Fig. 3, a diagram illustrating one use of my improved device in connection with automobile-engines of the internal-combustion type.

In the particular embodiment of my invention selected for illustration herein and shown in the drawings, A is a suitable support, preferably of insulating material, the same being provided with a post a, to which is suitably secured the armature-carrier b, shown as a flat spring, and to which is attached the armature c of the electromagnet C, the core of which protrudes through the support A. The movement of the armature and its carrier in an outward or retractile direction is limited by a stop, shown as the head of a stud d, carried by said support. This same stud may also provide an inner stop d' to limit the inward or attracted movement of the said armature, although the latter ordinarily may bring up against the end of the magnet-core, so that the latter in such case would constitute the stop for the movement of the armature in this direction.

Above the armature-carrier b, and it may be mounted upon the same post a therewith, is the circuit-controlling or contact member e, shown as a flat spring, perforated at its free end to receive loosely therethrough the shank of a stud f, fast upon the free end of the armature or its carrier b, the head of said stud f overlying the perforation in the contact member e, so that inward movement of said stud will by engagement of its head with said contact member cause the latter also to be moved. This contact member e at its outer face is usually provided with a contact-point g, which is in normal engagement with the fixed, though adjustable, screw h, mounted in a suitable yoke h', secured to the support A. In its normal position, with the armature c retracted and resting with its carrier against the head of the stop-stud d, the head of the small stud f is beyond and

away from the contact member *e*, as shown. Under these conditions if the magnet *C* be energized its armature will be attracted and will acquire considerable movement and 5 momentum before the head of the stud *f* meets and engages the contact-arm *e*, so that the said arm *e* is given a quick, positive, and pronounced movement away from the contact-screw *h*, breaking the circuit in a decisive 10 manner, such as will produce a pronounced and effective spark. The inward movement of the armature is positively stopped, as described, although ordinarily a positive stop or limit to the inward or attracted 15 movement of said armature is not highly important.

Upon the breaking of the magnetic circuit, as described, the magnet *C* is deenergized and its armature *c* under the influence of the resilient 20 nature of its carrier is retracted until stopped positively by the head of the stud *d*; but before the armature has completed its retractile movement the contact member *e* meets and is stopped by contact with the screw *h*, further retractile movement of the armature causing the head of the stud *f* to rise above the contact member *e* to the position shown in Fig. 1, the distance of said head above said contact member having to be 25 made up again upon the next succeeding opposite movement before the contact member *e* is moved. This movement of the armature beyond or independently of the contact member *e*, permitted in the present instance by 30 the lost motion between the head of the stud *f* and the contact member, permits me to employ a positive stop to limit the outward or retractile movement of the armature without danger of impairing the efficiency of the contact 35 or engagement between the contact-point *g* and contact-screw *h*, and by thus causing the said armature always to vibrate against a fixed stop *d* I obtain a certainty of movement with freedom from imperfect or incomplete 40 vibration, which is wholly lacking in devices for this purpose as heretofore constructed.

The lost motion between the armature and contact member or the movement of the armature 45 after the contact member has been stopped insures a closing of the circuit at each vibration for a sufficient time to produce a pronounced spark when the circuit is next broken, and the break when it occurs is decisive and pronounced, because the armature is already in motion and under considerable momentum before it engages the contact-arm.

In Fig. 3 I have illustrated diagrammatically 50 one method of connecting up my improved device, it being indicated by the letter *C*, in connection with each of a plurality of spark-coils 1 2, arranged in circuits 3 6,

which include a generator *B* and a circuit-controlling device *p''*, attached to the engine, 65 for instance, of an automobile, and which closes the circuits of the several coils in succession as required, there being one coil for each of the four cylinders of the engine. Sparking points are marked 13 14. Whenever 70 any of the circuits 3 6 is closed, the automatic making and breaking device *C* is set in operation to produce a rapid succession of impulses through the closed circuit, which by their decisive nature produce certain and 75 sufficient sparking between the points 13 14, thus insuring successful ignition of the motive-power mixture within the engine-cylinders.

My invention is not limited to the particular embodiment thereof here shown for illustrative purposes, but may be varied within the spirit and scope of the invention; nor is my invention restricted to any particular use, although it is especially useful in connection with internal-combustion engines for 80 automobiles and other purposes or wherever a sparking coil is used.

Having described one embodiment of my invention, without limiting myself to details, 85 what I claim, and desire to secure by Letters Patent, is—

1. An automatic circuit making and breaking device containing an electromagnet, its armature, and a resilient carrier therefor, a 90 resiliently-mounted contact member, a headed connection between said armature-carrier and contact member, and retractile stops for said armature-carrier and contact member, and arranged to provide a lost motion between the said headed connection and said contact member. 95

2. The combination with a sparking coil and spark-points, of a circuit making and breaking device in circuit therewith and comprising an electromagnet, its armature having a positive retractile stop and a contact member moved by said armature and having also a positive retractile stop with a lost motion between said armature and contact member upon attracted movement of one by the other. 105

3. An automatic circuit making and breaking device containing an electromagnet, an elastically-mounted armature member, a contact member, and means for causing engagement between said armature member and contact member after the former has acquired an appreciable momentum, said armature member having a relatively great mass in comparison with its resistance to the attraction of the armature, thereby quickly to acquire its momentum. 115

4. An automatic circuit making and breaking device comprising an electromagnet, a resiliently-mounted armature member, a posi- 120

tive stop for the retractile movement thereof, and a resiliently-mounted contact member adapted to be engaged by said armature member after the initial movement of the latter, 5 said armature member being between the magnet and said contact member.

In testimony whereof I have signed my

name to this specification in the presence of two subscribing witnesses.

ANDREW L. RIKER.
